G. W. LANCASTER

COUNTERBALANCING SASHES FOR STATIONARY WINDOW CASEMENTS

Filed Jan. 5, 1921

Inventor

George W. Lancaster,

P. A. Roswell,
his Attorney

UNITED STATES PATENT OFFICE.

GEORGE W. LANCASTER, OF RICHMOND, VIRGINIA, ASSIGNOR TO PERFECTED WINDOW COMPANY, OF RICHMOND, VIRGINIA, A CORPORATION.

COUNTERBALANCING SASHES FOR STATIONARY WINDOW CASEMENTS.

Application filed January 5, 1921. Serial No. 435,233.

To all whom it may concern:

Be it known that GEORGE W. LANCASTER, a citizen of the United States of America, residing at Richmond, county of Henrico, 5 and State of Virginia, has invented new and useful Counterbalancing Sashes for Stationary Window Casements, of which the following is a specification.

It is the purpose of the present invention 10 to provide counterbalancing sashes for stationary window casements, wherein the construction and arrangement and particularly the operation of the several counterbalancing sashes are improvements over those existing in the patent issued to George W. Lancaster the seventh day of December 1920, Patent No. 1,361,163, and those embodied in 15 the copending application of said George W. Lancaster, filed February 20, 1920, Serial 20 No. 360,151.

In the said copending application and the aforesaid patent the upper one of the auxiliary sashes is counterbalanced by another of said auxiliary sashes, by means of a detachable connection with the second auxiliary sash. In other words the connection is 25 adjustable relatively to the second auxiliary sash, so that the upper sash may be opened independently of the other sashes, for ventilation.

Through extensive experience and a wide application of this principle of adjustment of sashes, either for stationary window casements or for auxiliary sashes for swinging 35 sashes, it has been found that the projections on one of the sashes, to which a detachable connection is made are not practical for the purpose. It has been found that they are in the way, very dangerous, particularly 40 to the extent of snagging or cutting the hands of those who may operate the sashes, and furthermore impractical by reason of the detachable connections becoming accidentally disconnected, resulting in the upper outermost sash dropping substantially the 45 height of the window, which is very liable to cause the breaking of the pane of glass. Also it has been found that it is more or less expensive to construct the projections on the side rail of the sash.

It is the aim of the present invention to overcome these disadvantages, and to provide connections between certain of the coun-

terbalancing sashes, whereby the balancing and the adjustment of the sashes are greatly 55 facilitated.

Another purpose is to provide means operatively mounted on guides of the window casement and carrying projections and being movable with one of the sashes, so that 60 through the medium of operative connections with the uppermost sash, the latter may be adjusted correspondingly with the movement of said means. This means also include projections with which a member of 65 said operative connections selectively engages to operate said uppermost sash. The guides act to guard the projections, and thereby prevent said projections from snagging or otherwise injuring the hands of 70 those who may operate the sashes.

A further purpose is the provision of a slide movably carrying a counterbalancing sash, and to which the connections between upper outermost and lower innermost sashes 75 are detachably connected, so that the uppermost sash may be lowered for ventilation, adjustably with relation to the inner lowermost counterbalancing sash, which may be closed, or partly opened.

A still further purpose accomplished by virtue of this construction, is that the inner lowermost sash may be opened manually independently of the upper outermost sash temporarily, without in any way disturbing 85 the upper sash.

Additionally it is the aim to provide means for facilitating the removal of the several sashes, namely to provide guides, of sectional construction and involving arrangement, whereby the guides may be easily removed, to permit the sashes to be removed and replaced.

It is to be understood that the particulars herein given are in no way limitative and 95 that while still keeping within the scope of the invention, any desired modifications of detail and desired proportions may be made in the apparatus according to circumstances.

The invention comprises further features 100 and combination of parts, as will be herein-after set forth, shown in the drawings and claimed.

In the drawings:

Figure 1 is a vertical sectional view 105 through a conventional form of stationary

window casement, showing the application of the counterbalancing sashes.

Figure 2 is a sectional view on line 2—2 of Figure 1.

5 Figure 3 is an enlarged detail perspective view of a portion of the stationary window casement, showing sections of the guides, and also illustrating the detachable connections between the sash cords and the lower innermost sash.

10 Figure 4 is a detail perspective view of the lower portion of several of the guides, showing the slide, which supports one of the sashes.

15 Figure 5 is a detail perspective view of the lower portion of several of the guides, also showing the lower part of one of the slides.

Figure 6 is a detail perspective view of one of the slides.

20 Referring to the drawings, 1 designates the wall of the building and 2 an opening therein, and 3 denotes a window casement, which, in the present instance is stationary, and is adapted to carry a plurality of counterbalancing sashes. The window casement 3 is provided with a plurality of vertical guides 4 on opposite vertical sides, which consists of a plurality of sheet metal channels arranged in parallelism.

25 30 In order to provide a firm structure of channels, they are fastened together in any suitable manner, preferably by spot welding, as indicated at 5. The channels or guides of each side of the window casement consist of upper and lower sections 6 and 7. The upper sections of channels are fixed stationary relatively to the window casement in any suitable manner preferably by spot welding 8, or by any other suitable means

35 40 (not shown), whereby the upper section of channels may be removed, if it is so desired. The lower section of channels are preferably detachable relatively to the window casement, though it is obvious that they may

45 50 be made stationary. In order to render the lower sections of channels removable, they are secured to the casement by means of screws 9, which pass through certain of the channels or guides, through the metal wall

55 60 of the casement, and into the upper and lower heavy bars 10. These bars 10 are fastened to the inner surface of the window casement preferably by spot welding, as indicated at 11, though other means may be

65 70 employed. The reason for providing the heavy bars is that the casement is constructed of relatively thin sheet metal, which would not hold the screws 9 with sufficient security to hold the channels or guides in place, hence

75 80 the heavy bars 10, in order to provide sufficient backing to hold the screws. The purpose of constructing the channels or guides in sections, and rendering the upper sections of channels detachable or removable, is to

85 90 permit the counterbalancing sashes to be eas-

ily removed or replaced, or new ones inserted. Obviously by removing the screws 9 the lower sections of channels or guides may be removed readily, and then by lowering the counterbalancing sashes to a point below the upper sections of channels, the sashes may be removed for repairs, or for substituting new ones, or for connecting the counterbalancing sashes by means of sash cords or cables, chains or the like. While the channels or guides are mounted on a stationary casement, it is obvious that they may be applied to movable or swinging dominant window sashes.

95 100 105 Mounted in the channels or guides adjacent the interior of the room or adjacent the inner surface of the wall or window casement are vertically movable end members of a slide 12 clearly shown in Figures 3 and 6. Only one end member is indicated, though it is obvious that two are employed in actual practice. The end member is constructed of sheet metal, preferably steel and comprises inwardly and outwardly facing channels 13 and 14. The channel 14 of the end member straddles the adjacent flanges of two adjacent channels or guides of the casement, while the wall of the channel 13 fits into one of the adjacent channels or guides. The end member adjacent the channel 14 has an elongated flange 15, which rides or moves in the innermost channel or guide of the casement. The end member is capable of moving the full height of the window casement, for the purpose of adjusting the lower innermost sash. Though only one end member is illustrated, it is obvious that by means of a transverse bar or strip 16, the end member which is illustrated, is designed to be connected to an opposite end member (not shown). Both end members connected by the bar 16, as a whole, constitute a slide for actuating the lower innermost sash. By means of the bar or strip, which engages a groove 17 in the lower wall of the window casement air is precluded from the interior of the room, when the lower innermost sash is closed. For instance the bar 16 engages the groove 17, so that when the lower innermost sash is closed, it contacts with the bar, obviously preventing the air or wind from entering.

110 115 120 125 130 The inner lowermost sash engages the bar 16 as long as it is resting upon the end or bottom walls of the slide, regardless of the position of the slide, namely, whether it is in a raised or lowered position. However when the slide is in a lowered position and the bar 16 engaged with the groove 17, the bar 16 is retained tight against the lower rail of the inner lowermost sash. The inner lowermost sash may be raised relatively to the slide, and in this case the lower rail of the inner lowermost sash will disengage

from the bar 16. The lower end of the channel 13 of each end member 12 of the slide is closed by means of the end wall 18.

Mounted in certain of the several channels or guides are upper outermost and two intermediate counterbalancing sashes 19 and 20—20, and mounted in the channels of the end members 12, only one of which is shown is an inner lowermost sash 21, which as previously stated engages the outer face of the transverse bar 16, in order to preclude the air or wind. Mounted or supported in any suitable manner in the upper part of the casement, which may, if it is so desired, constitute the dominant sash movable in any suitable manner, are pulleys 22 and 23. Passing over the pulleys 22 is a cable, chain or sash cord or the like 24, which is connected to the upper outermost sash 19, and 20 is in turn connected to a transverse bar or rod 31.

Passing over the pulley 23, is a cable, sash cord or chain 25, which has its opposite ends connected in any suitable manner as 25 at 27 to the upper rails of the two intermediate or adjacent sashes as shown. By means of this cable, chain or sash cord 25, the two intermediate sashes are relatively counterbalanced. Obviously, the movement 30 of one of the intermediate sashes causes movement of the other and vice versa. The sashes are capable of being disposed in different relative positions, for ventilating purposes. The several counterbalancing 35 sashes are connected by the interengaging flanges 28, which act to preclude the air or wind, dust and the like, when the counterbalancing sashes are closed. Any other interlocking means may be employed for connecting the sashes.

One wall of the channel 14 of each end member 12 is provided with a plurality of projecting ears or lugs 29, and an additional ear or lug 30. The lug or ear 30 is disposed 45 adjacent the upper portion of the end member, and extends the full length or full distance between the wall of the channel 14 and the innermost flange of the innermost channel or guide of the window casement. 50 The arms or lugs 29 extend from the same wall of the end member 12, but extend only half the distance between the wall of the channel 14 and the inner surface of the innermost flange of the innermost channel or guide. It is possible to move or adjust the 55 bar 31 to engage any two opposite arms or lugs 29 and 30, and when the bar 31 is so adjusted the upper outermost sash may be lowered, without moving the slide. However 60 should the bar 31 be moved from engagement with the lower arms or lugs 29 to engagement with the upper arms 29, the upper outermost sash is first lowered, after which, by virtue of the bar 31 being moved 65 with the end members 12 of the slide, the

latter will be moved, hence lowering the upper outermost sash to any desired position. By engaging the bar 31 with the lugs or arms 30, and then by moving the slide, the inner lowermost and outer uppermost sashes may be adjusted a maximum distance to insure a thorough ventilation. When the bar 31 is disengaged from certain of the arms, it is possible to pass the bar 70 between the arms and the flange of the innermost channel, in order to permit the bar to be moved or adjusted vertically. 75

By means of the lower end of the channel 13 of the end member being closed, the lower innermost sash 21 is supported, so 80 that when the slide as a whole is moved vertically in its guides or channels, the lower innermost sash is likewise moved.

If pressure is applied to the upper edge 85 of the upper intermediate sash, the upper outermost sash is lowered, and the other intermediate and lower innermost sashes are raised, owing to the interlocking flanges of the sashes. It is possible to raise the lower innermost sash independent of the slide, that 90 is temporarily, but when the slide as a whole is moved, the lower innermost sash simultaneously moves. It is obvious that the lower innermost sash may be raised to a position above said slide, after which the sash 95 may be disposed in an angular position, so that one edge of the lower innermost sash may rest upon the upper end of the slide, thereby supporting the lower innermost sash in a raised position independently of the 100 slide.

It is obvious that by removing the screws 9, the lower sections of channels or guides may be easily detached, allowing removal or replacement of the several auxiliary 105 sashes. The adjoining ends of the upper and lower sections are shown, as indicated at 32. The bar 31 may be constructed of any suitable material, preferably steel or other suitable metal, and may be supplied 110 with extra weight, so as to counterbalance with the upper outermost sash. In other words the bar 31 may be thick enough, either at its ends or throughout its length, so as to counterbalance with the upper 115 outermost sash. For instance by tilting the bar 31, so as to disengage the ends from the projections 29 or 30, the bar 31 may be moved, and raised to a position above the slide, then the outer uppermost sash may be lowered the full distance of the window casement independent of the lower sash. By means of the upper outermost sash being counterbalanced with the slides and the bar, it is possible to insure a wide range of 120 ventilation. The upper outermost sash closes against a bar 33, which connects the outermost channels or guides of the window casement at their upper ends, thereby precluding the air or wind. 125 130

In constructing the various joints, namely the channels of the upper, lower and intermediate sashes, putty or some similar material may be used to preclude the weather, and to act as an agent to prevent metal binding, particularly where the metal contacts with fragile material such as glass. In the overlapping joints 28, as well as where the side walls of the stationary window casement engage in the wall of the structure, any suitable material, preferably asbestos in any form, either in a moist pliable state, or in a dry more or less fibrous condition may be used. It has been found that asbestos in any form or condition constitutes a better agent for precluding the weather. The sash cords or cables may be constructed of any suitable material, either rope or in the form of chains, or in the form of metallic cables, such as copper, in a more or less pliable condition, so as to easily pass over the pulleys, thereby preventing a binding and permitting the sashes to move freely.

25 The stationary casement may be constructed of any suitable sheet metal, preferably rolled sheet steel, rolled in any angular form, and furthermore in constructing the casement, or the channel sashes for the glasses, it is desirable to afford any form of refinement, or trimming, such as rolled or beaded edges or the like, in order to present a neat appearance.

Also in fitting the glasses in the channels of the sashes putty or some similar material has been used up to the present time, and it has been found that in using this form of material, that the glasses are not held firm and secure, particularly when the putty or similar material dries out; furthermore in using putty or similar material it is very difficult to obtain a very close or tight joint between the parts, particularly where the glasses engage the channels of the sashes.

40 Therefore in the present invention it is desirable to use asbestos in any form or condition, to insure better and tighter joints between all parts, whether they be fixed or separable joints. It has been found that asbestos in a moist pliable condition is more preferable in the present case.

While the channel guides for the sashes are described and shown as being constructed from channel strips fastened together, 55 most preferably used in hand made structures of this character, it is particularly desirable to roll these parts from single pieces of sheet metal, in order to provide refinements for the structure, as well as otherwise reducing the cost of manufacture, which in turn will lower the selling price.

The invention having been set forth, what is claimed is:

1. In a window construction, a frame having opposed vertical guides, counterbalanc-

ing sashes movable in the guides, a slide frame movable in certain of said guides and provided with means for supporting one of the sashes, said sash being freely removable from said supporting means and a connection between another of the sashes and the slide, whereby the other sash and the slide may be moved simultaneously. 70

2. In a window construction, a frame having opposed vertical guides, counterbalancing sashes movable in the guides, a slide in certain of said guides having removably mounted therein one of the sashes and a connection between another of the sashes and the slide, whereby the latter sash and the slide may be moved simultaneously, the construction and arrangement of the connection being such that it is adjustable relatively to the slide, whereby said latter sash may be adjusted relatively to the slide without moving the sash which is mounted in the slide. 75

3. In a window construction, a frame having opposed guides, a slide mounted in certain of the opposite guides, opposed sashes, one mounted in the guides, the other sash removably mounted in the slide, said slide having projections, sash cords connected to the sash in the guides of the frame and having means to selectively engage with certain of said projections, whereby the slide carried sash may be adjusted independently of the slide, or the slide and its sash may be adjusted to counterbalance with the sash which is mounted in guides of the frame. 95

4. In a window construction, a frame having opposed guides, a slide mounted in certain of the opposite guides, opposed sashes, one mounted in the guides, the other sash removably disposed in the slide, said slide having projections, sash cords connected to the sash in the guides of the frame and having means to selectively engage with said projections, whereby the slide carried sash may be adjusted independently of the slide, or the slide and its sash may be adjusted to counterbalance with the sash which is mounted in the guides of the frame, and means carried by the slide to cause the sash which is disposed therein to move with the 115 slide.

5. In a window construction, a frame, having opposite guides, a slide having guides and engaging certain of the opposite guides of the frame, a lowermost sash movable in the guides of said slide, the lower ends of the guides of the slide having means to support said lowermost sash to move with the slide, an uppermost sash, sash cords connected to the last named sash, and means for detachably and adjustably connecting the sash cords to the slide, whereby adjustment of the sash cords will adjust the uppermost sash independently of and relatively to the slide.

from the bar 16. The lower end of the channel 13 of each end member 12 of the slide is closed by means of the end wall 18.

Mounted in certain of the several channels or guides are upper outermost and two intermediate counterbalancing sashes 19 and 20—20, and mounted in the channels of the end members 12, only one of which is shown is an inner lowermost sash 21, which as previously stated engages the outer face of the transverse bar 16, in order to preclude the air or wind. Mounted or supported in any suitable manner in the upper part of the casement, which may, if it is so desired, constitute the dominant sash movable in any suitable manner, are pulleys 22 and 23. Passing over the pulleys 22 is a cable, chain or sash cord or the like 24, which is connected to the upper outermost sash 19, and 20 is in turn connected to a transverse bar or rod 31.

Passing over the pulley 23, is a cable, sash cord or chain 25, which has its opposite ends connected in any suitable manner as 25 at 27 to the upper rails of the two intermediate or adjacent sashes as shown. By means of this cable, chain or sash cord 25, the two intermediate sashes are relatively counterbalanced. Obviously, the movement 30 of one of the intermediate sashes causes movement of the other and vice versa. The sashes are capable of being disposed in different relative positions, for ventilating purposes. The several counterbalancing 35 sashes are connected by the interengaging flanges 28, which act to preclude the air or wind, dust and the like, when the counterbalancing sashes are closed. Any other interlocking means may be employed for connecting the sashes.

One wall of the channel 14 of each end member 12 is provided with a plurality of projecting ears or lugs 29, and an additional ear or lug 30. The lug or ear 30 is disposed 45 adjacent the upper portion of the end member, and extends the full length or full distance between the wall of the channel 14 and the innermost flange of the innermost channel or guide of the window casement. 50 The arms or lugs 29 extend from the same wall of the end member 12, but extend only half the distance between the wall of the channel 14 and the inner surface of the innermost flange of the innermost channel or guide. It is possible to move or adjust the 55 bar 31 to engage any two opposite arms or lugs 29 and 30, and when the bar 31 is so adjusted the upper outermost sash may be lowered, without moving the slide. However should the bar 31 be moved from engagement with the lower arms or lugs 29 to engagement with the upper arms 29, the upper outermost sash is first lowered, after 60 which, by virtue of the bar 31 being moved with the end members 12 of the slide, the

latter will be moved, hence lowering the upper outermost sash to any desired position. By engaging the bar 31 with the lugs or arms 30, and then by moving the slide, the inner lowermost and outer uppermost 70 sashes may be adjusted a maximum distance to insure a thorough ventilation. When the bar 31 is disengaged from certain of the arms, it is possible to pass the bar between the arms and the flange of the innermost channel, in order to permit the bar 75 to be moved or adjusted vertically.

By means of the lower end of the channel 13 of the end member being closed, the lower innermost sash 21 is supported, so 80 that when the slide as a whole is moved vertically in its guides or channels, the lower innermost sash is likewise moved.

If pressure is applied to the upper edge 85 of the upper intermediate sash, the upper outermost sash is lowered, and the other intermediate and lower innermost sashes are raised, owing to the interlocking flanges of the sashes. It is possible to raise the lower innermost sash independent of the slide, that 90 is temporarily, but when the slide as a whole is moved, the lower innermost sash simultaneously moves. It is obvious that the lower innermost sash may be raised to a position above said slide, after which the sash 95 may be disposed in an angular position, so that one edge of the lower innermost sash may rest upon the upper end of the slide, thereby supporting the lower innermost sash 100 in a raised position independently of the slide.

It is obvious that by removing the screws 9, the lower sections of channels or guides may be easily detached, allowing removal or replacement of the several auxiliary 105 sashes. The adjoining ends of the upper and lower sections are shown, as indicated at 32. The bar 31 may be constructed of any suitable material, preferably steel or other suitable metal, and may be supplied 110 with extra weight, so as to counterbalance with the upper outermost sash. In other words the bar 31 may be thick enough, either at its ends or throughout its length, so as to counterbalance with the upper 115 outermost sash. For instance by tilting the bar 31, so as to disengage the ends from the projections 29 or 30, the bar 31 may be moved, and raised to a position above the slide, then the outer uppermost sash may 120 be lowered the full distance of the window casement independent of the lower sash. By means of the upper outermost sash being counterbalanced with the slides and the bar, it is possible to insure a wide range of 125 ventilation. The upper outermost sash closes against a bar 33, which connects the outermost channels or guides of the window casement at their upper ends, thereby precluding the air or wind. 130

In constructing the various joints, namely the channels of the upper, lower and intermediate sashes, putty or some similar material may be used to preclude the weather, and to act as an agent to prevent metal binding, particularly where the metal contacts with fragile material such as glass. In the overlapping joints 28, as well as where the side walls of the stationary window casement engage in the wall of the structure, any suitable material, preferably asbestos in any form, either in a moist pliable state, or in a dry more or less fibrous condition may be used. It has been found that asbestos in any form or condition constitutes a better agent for precluding the weather. The sash cords or cables may be constructed of any suitable material, either rope or in the form of chains, or in the form of metallic cables, such as copper, in a more or less pliable condition, so as to easily pass over the pulleys, thereby preventing a binding and permitting the sashes to move freely.

25 The stationary casement may be constructed of any suitable sheet metal, preferably rolled sheet steel, rolled in any angular form, and furthermore in constructing the casement, or the channel sashes for the glasses, it is desirable to afford any form of refinement, or trimming, such as rolled or beaded edges or the like, in order to present a neat appearance.

Also in fitting the glasses in the channels of the sashes putty or some similar material has been used up to the present time, and it has been found that in using this form of material, that the glasses are not held firm and secure, particularly when the putty or similar material dries out; furthermore in using putty or similar material it is very difficult to obtain a very close or tight joint between the parts, particularly where the glasses engage the channels of the sashes.

45 Therefore in the present invention it is desirable to use asbestos in any form or condition, to insure better and tighter joints between all parts, whether they be fixed or separable joints. It has been found that asbestos in a moist pliable condition is more preferable in the present case.

While the channel guides for the sashes are described and shown as being constructed from channel strips fastened together, most preferably used in hand made structures of this character, it is particularly desirable to roll these parts from single pieces of sheet metal, in order to provide refinements for the structure, as well as otherwise reducing the cost of manufacture, which in turn will lower the selling price.

The invention having been set forth, what is claimed is:

1. In a window construction, a frame having opposed vertical guides, counterbalanc-

ing sashes movable in the guides, a slide frame movable in certain of said guides and provided with means for supporting one of the sashes, said sash being freely removable from said supporting means and a connection between another of the sashes and the slide, whereby the other sash and the slide may be moved simultaneously. 70

2. In a window construction, a frame having opposed vertical guides, counterbalancing sashes movable in the guides, a slide in certain of said guides having removably mounted therein one of the sashes and a connection between another of the sashes and the slide, whereby the latter sash and the slide may be moved simultaneously, the construction and arrangement of the connection being such that it is adjustable relatively to the slide, whereby said latter sash may be adjusted relatively to the slide without moving the sash which is mounted in the slide. 75

3. In a window construction, a frame having opposed guides, a slide mounted in certain of the opposite guides, opposed sashes, one mounted in the guides, the other sash removably mounted in the slide, said slide having projections, sash cords connected to the sash in the guides of the frame and having means to selectively engage with certain of said projections, whereby the slide carried sash may be adjusted independently of the slide, or the slide and its sash may be adjusted to counterbalance with the sash which is mounted in guides of the frame. 85

4. In a window construction, a frame having opposed guides, a slide mounted in certain of the opposite guides, opposed sashes, one mounted in the guides, the other sash removably disposed in the slide, said slide having projections, sash cords connected to the sash in the guides of the frame and having means to selectively engage with said projections, whereby the slide carried sash may be adjusted independently of the slide, or the slide and its sash may be adjusted to counterbalance with the sash which is mounted in the guides of the frame, and means carried by the slide to cause the sash which is disposed therein to move with the slide. 115

5. In a window construction, a frame, having opposite guides, a slide having guides and engaging certain of the opposite guides of the frame, a lowermost sash movable in the guides of said slide, the lower ends of the guides of the slide having means to support said lowermost sash to move with the slide, an uppermost sash, sash cords connected to the last named sash, and means for detachably and adjustably connecting the sash cords to the slide, whereby adjustment of the sash cords will adjust the uppermost sash independently of and relatively to the slide.

6. In a window construction, a frame, having opposite guides, a slide having guides and engaging certain of the opposite guides of the frame, a lowermost sash movable in the guides of said slide, the lower ends of the guides of the slide having means to support said lowermost sash to move with the slide, an uppermost sash, sash cords connected to the last named sash, and means for detachably and adjustably connecting the sash cords to the slide, whereby adjustment of the sash cords will adjust the uppermost sash independently of and relatively to the slide, the construction and arrangement of the detachable means for the sash cords being such that the slide and the lowermost sash may act to counterbalance the uppermost sash.

7. In a window construction, a casement provided with opposed vertical guides, a slide engaging certain of the guides, a sash guided in the slide, means carried by the slide for supporting the sash movably with the slide, said sash being movable vertically with respect to the slide, another sash mounted in certain of the guides of the casement, and means connected to the second sash and having adjustable connections with the slide, whereby the last mentioned sash and said slide may counterbalance the other sash.

8. In a window construction, a casement having opposite guides, a slide having means operatively mounted on certain of said opposite guides, a sash operatively mounted upon the slide, which is provided with means for supporting the sash with respect to the slide, said slide including means at its lower portion engageable with the bottom of the casement and with the lower rail of the sash, to preclude the weather.

9. In a window construction, a casement having opposite guides, a slide having means operatively mounted on certain of said opposite guides, a sash operatively mounted upon the slide, which is provided with means for supporting the sash with respect to the slide, said slide including means at its lower portion engageable with the bottom of the casement and with the lower rail of the sash, to preclude the weather, a second sash, means connected to the second sash and provided with selective connections with the slide, whereby the first mentioned sash and said slide may counterbalance the other sash.

55 10. In a window construction, a casement provided with opposite guides, a slide provided with means operatively mounted in certain of the opposite guides, a sash operatively supported on the slide, a second sash mounted in certain of said guides, means

connected to the second sash and provided with selective operative connections with the slide, whereby the second mentioned sash may counterbalance the other sash and its slide.

65

11. In a window construction, a frame having opposed vertical guides, a slide frame engaging with certain of said opposed guides, and provided with guides, counterbalancing sashes, certain thereof being mounted in other of the guides of said frame, and certain other of said sashes being mounted in the guides of the slide frame and freely removable therefrom, and raising and lowering means connected to the former of the sashes and adapted to connect with and disconnect from said slide frame, whereby the latter of the sashes and the slide frame may raise and lower with the former.

12. In a window construction, a frame having opposed vertical guides, a slide frame having guides and being movable on certain of said guides, counterbalancing sashes, one of which is mounted in the guides of the slide, the others of which are mounted for movement in others of the guides of said frame, raising and lowering means connected to one of said others of the sashes, said raising and lowering means having selective connections with the slide for varying the relation between the slide and its associated sash and the sash to which said raising and lowering means are connected.

13. In a window construction, a frame having opposed vertical guides, a slide having guides and being movable on certain of said guides, counterbalancing sashes, one of which is mounted in the guides of the slide, the others of which are mounted for movement in others of the guides of said frame, raising and lowering means connected to one of said others of the sashes, said raising and lowering means having selective connections with the slide for varying the relation between the slide and its associated sash and the sash to which said raising and lowering means are connected, said raising and lowering means being disconnectable from the slide and including a member by which the sash to which the raising and lowering means are connected may be lowered the full height of the frame.

In witness whereof, in the presence of two witnesses, the inventor's signature is hereunto affixed.

GEORGE W. LANCASTER.
